FINGER RING WITH A SHANK HAVING SET ATTACHING, GEM SUPPORTING PRONGS

Raymond G. Luttrario, Providence, R. I., assignor to Uncas Manufacturing Company, a corporation of Rhode Island

Application February 15, 1955, Serial No. 488,263

2 Claims. (Cl. 63—15.7)

This invention relates to a finger ring, particularly a finger ring having a box type setting for a gem and/or the like.

Finger rings of this general type are usually made of separate elements which are secured to each other as by solder. The soldering operation requires skilled labor and is also a disagreeable operation in that the worker frequently suffers burns in performing the operation.

An object of the invention is to provide a finger ring of the above type so constructed as to completely eliminate the above soldering operation.

A more specific object of the invention is to provide a finger ring wherein the gem setting portion will be secured to the ring shank by clamping the walls of the setting between portions of the ring shank.

Another object is to provide a construction in which the gem will additionally function to bind the ring shank and gem setting to each other.

With these and other objects in view, the invention consists of certain novel features of constructions as will be more fully described and particularly pointed out in the appended claims.

In the accompany drawings:

Figure 1 is a front elevation of a finger ring embodying my invention;

Figure 2 is a similar view but showing the gem setting portion of the ring in section;

Figure 3 is a perspective view of the gem setting;

Figure 4 is a perspective view of the ring shank; and

Figure 5 is an elevational view partially in section showing the gem setting and ring shank in assembled relation prior to the ends of the ring shank being secured to the walls of the setting.

The shank of the finger ring according to the present invention is made in the form of a split annulus with the ends flattened so as to form a shoulder. The gem setting is of a box type which may be of any desired shape, as by way of example generally rectangular, and has oppositely aligned openings pierced through opposite walls adjacent to the bottom wall of the setting. The flattened end portion of the ring shank is inserted in said openings with the said shoulders providing abutments to engage the edges of the openings. The flattened portions extend within the setting and are bent to clench the same against the adjacent walls to clamp and secure the setting between the said shoulders.

Referring to the drawing for a more detailed description of the invention, 10 designates a finger ring having a shank 11 to which is secured a gem setting 12 for a gem 13 which is secured in position by fingers or prongs 14 which are bent over the gem in the known manner.

The shank 11 is made in one piece of suitable strip stock having the desired shape in cross section. The end portions of the strip are flattened as at 15 so as to form shoulders 16, and the strip is bent circularly so as to form a split annulus (see Figure 4). The setting 12 is of the box type and may be made of any of various shapes appropriate to a ring setting. As by way of example,

2

the setting 12 may be generally rectangular, circular, oval, or polygonal as shown having side walls 17, 18, 19, 20, and a bottom wall 21.

The side walls 17, 18 are each provided with a generally rectangular opening 22 which is of a shape and size to substantially correspond to the cross section of the flattened end portions 15. The lower edge of the openings 22 extend substantially flush with the inner side of the bottom wall 21 and are in line with each other at a position centrally of the walls 17, 18. The bottom wall 21 has a pair of openings 23 therethrough which are positioned adjacent the walls 17, 18 and in line with the openings 22.

In assembling the shank or annulus 11 and the setting 12, the annulus is spread apart sufficiently for the flattened ends 15 to be inserted through the openings 22 with the shoulders 16 abutting against the edges of the walls 17 and 18 (see Figure 5). The ends 15 may now be bent upwardly to be clenched against the adjacent wall portions so as to securely clamp the said wall 17, 18 between the ends 15 and shoulders 16 in the known manner. The gem or ornament 13 may now be positioned in the setting 12 and the prongs 14 bent over the edges of the gem 13 to hold the same in position in the known manner. In bending the ends 15 to clench the same in place, the tool or tools employed (not shown) may be inserted through the openings 23 to engage and bend said ends 15.

As will be seen in Figure 2, the portions 15 of the ring shank extend to near the upper edge of the setting 12 and are engaged with the lower side portions of the gem 13. Thus, the portions 15 are additionally clamped between the walls of the setting 12 and gem 13. This assures a secure binding of the ring elements to each other. Should there be an improper bending or clinching of the portions 15, the gem when being set or secured in place will engage such improperly bent portions 15 and force the same or complete the bending thereof firmly into proper position.

From the foregoing description it will be apparent that I have disclosed a two-piece ring which may be easily assembled and secured to each other without a solder operation. It will be further apparent that the ring after assembly may be further processed to finish the same ready to receive the gem.

I claim:

1. A finger ring comprising a gem setting having bottom, side, and end walls, the upper edges of said side and end walls providing a seat for receiving a gem, said side walls having an opening therethrough at the lower portion thereof, a split annulus having the end portions thereof flattened inwardly from the outer side thereof, said flattened end portions extending through said openings and bent upwardly in the plane of the annulus about an axis parallel to the flattened end against said side walls, said openings being of a shape corresponding to the shape of the flattened ends to prevent rotation, and a stone engaged with said end portions to additionally bind said portions securely in place, and fingers on said side and end walls engaging said gem and securing the same in said setting.
2. A finger ring as set forth in claim 1 wherein said bottom wall has openings therethrough through which a tool may be inserted for engaging and bending said flattened portions against said side walls.
